6 Claims. (Cl. 104—124)

1

This invention relates to flexible trestlework designed for transporting material over a foundation which is subject to sinking or heaving by virtue of elastic characteristics or frost action.

It has heretofore been considered essential to provide load supporting trestlework with a foundation which has no tendency to sink and is not subject to lifting by frost action. Thus the trestlework in bridging is usually supported on solid piles extending to bed rock and trestlework conveyors have been provided with a solid base such as a cement block for each bent of the trestlework. Because of the expense involved, trestlework conveyors have not heretofore been used for long hauls.

According to the present invention, there is provided a trestlework conveyor which is flexible, the bents and longitudinals being so interconnected that if the foundation subsides beneath a bent it is not left suspended by its connection to the remainder of the trestlework, but sinks with the foundation without impairing the connection of the bent to the remainder of the trestlework. Thus, a flexible trestlework conveyor according to the invention comprises at least one, and preferably a plurality of trestle sections, each section comprising a plurality of transverse bents, longitudinal members connecting the bents near the top and a plurality of diagonal braces pivotally connected at one end to a longitudinal member and at the other end pivotally connected to means connected to a bent and movable upwardly or downwardly with respect to such bent. Each end bent of each trestle is connected to the adjacent bent by a strut or the like, and each other bent is provided at each side of each trestle section with a pair of diagonal braces pivotally connected to the respective longitudinal members at each side of each such bent and pivotally connected at the other end to the means which move with respect to the bent, such movement being upwardly towards the longitudinal members or downwardly away therefrom. In each section, one of the bents is fixedly connected to foundation blocks and the remaining bents are mounted on foundation blocks to slide longitudinally of the trestlework, means being provided to prevent such sliding bents from moving sideways of the trestlework. The sections are spaced to permit each section to expand from its fixed bent towards each end and preferably the end bents of adjacent sections are mounted (slidably) on common foundation blocks. The space between sections is bridged by rails supported on the longitudinals, the rails

2

being split at the point of bridging and connected to permit relative longitudinal movement of the rails carried by the adjacent trestle sections while maintaining wheel-bearing surfaces.

Each bent provided with a pair of diagonal braces as mentioned above has connected thereto a bracket having an upwardly extending slot adapted to engage a pivot member free to move up and down in such slot. The braces of a pair are both mounted on such pivot member.

According to the preferred modification, each bent includes a lower transverse member, upright members and a cap connected thereto supporting two longitudinal members, each carrying a rail for a wheeled car, the longitudinals and rails being spaced to carry such car. (It will be understood that each longitudinal and each rail may be, and usually is made up of many sections placed end to end.) A second pair of longitudinals spaced the same distance as the upper longitudinals mentioned above is slung below the upper longitudinals, each lower longitudinal being supported from the cap of each bent by suspension means and carrying rails of the same gauge as the upper rails. The lower longitudinals are further supported by a plurality of diagonal ties pivotally connected at the top to the upper longitudinals and at the bottom to the lower longitudinals.

The arrangement is such that a car carried on the rails has a load suspended from it. Accordingly the loaded car or cars travel on the lower rails and make the return journey on the upper rails. At each end rail extensions are provided constituting a ramp for transferring a car from the lower rails to the top rails and vice versa.

Other features of the invention will appear from the accompanying drawings, in which

Figure 1 is an elevation of the trestlework conveyor according to the invention showing part of the loading end section and all but one bent of the sections between the loading and unloading end sections broken away as well as portions of the diagonal braces and the upper longitudinals opposite the rail extensions.

Figure 2 is a section on the line 2—2 of Figure 1.

Figure 3 is an elevation of the rail expansion joint.

Figure 4 is a plan of the rail expansion joint.

Figure 5 is a detailed view showing the sliding connection of the diagonal braces to a bent.

Figure 6 is a section on the line 6—6 of Figure 5.

Figure 7 is a detailed plan view of the ramp-forming rail extension arrangement.

Figure 8 is an elevation corresponding to Figure 7.

The trestlework which may be many miles in length is composed of a plurality of sections. For convenience the section at one end is referred to as the loading section and that at the other end as the unloading section and the intervening sections constitute the travelling zone. The unloading and loading sections differ only from the remaining sections in that the former are provided with the ramp-forming rail extensions and are slightly modified to accommodate the same as hereinafter set forth. The complete unloading section of Figure 1 is indicated by the bracket A. Thus each section of the trestlework consists essentially of bents 10, foundation blocks 11, upper longitudinals 12, lower longitudinals 13 and diagonal braces 14.

Referring to Figure 2 each bent consists of a transverse beam 15 supported at each side on a foundation block 11, two uprights 16, a cap 17, two intermediate stub struts 18 and two struts 19. The uprights 16 are secured to the transverse members 15 and 17 by straps 16a of iron or the like nailed thereto, and the members 18 are nailed to the uprights 16. The struts 19 are similarly secured at the top to the cap 17, at the bottom to the transverse beam 15, and intermediate their lengths to the upright member 16.

One bent in each section is fixed against movement longitudinally of the trestlework, its transverse beam 15 secured by nails or the like, to its foundation block 11. The remaining bents of the section are mounted so that they may slide longitudinally of the trestlework, movement laterally of the trestlework being prevented in this case by auxiliary blocks 20 secured to the transverse beam 15 on each side of the respective foundation block 11.

As appears from Figure 2, each cap 17 carries two longitudinals 12 which connect the series of bents at the top, the longitudinals each carrying a rail 21 for a car 22 having flanged wheels 23 driven by motor 24 and the longitudinals being spaced in accordance with the tread of the car. Spaced exactly the same distance and carrying rails 25 are lower longitudinals 13. These longitudinals 13 are accurately spaced from the upright 16 by means of the stub struts 18 to which they are connected, and are supported from the caps 17 by rods 26, which, passed through holes provided in the caps 17 and the longitudinals 13, are connected by washers 27 and nuts 28, positioned at the top of the caps 17 and the bottom of the longitudinals 13. The lower longitudinals are further supported by diagonal ties 29 (see Figure 1) connected at the top to the upper longitudinals 12 and at the bottom to the lower longitudinals 13.

The end two bents of each section are connected together near the bottom by longitudinal struts 30. The remainder of the bents are not directly connected together at the bottom but are supported in the upright position by diagonal braces 14, each pivotally connected at the top to the respective longitudinal 12 by a bolt 31. Each diagonal brace 14 is pivotally connected at the bottom to the adjacent bent by the arrangement shown in detail in Figures 5 and 6. Bracket 32 of approximately inverted U-shape is connected at the ends to each of the struts 19 by means of bolts 33. Each bracket 32 is provided with an elongated slot 34, which runs longitudinally of the strut 19.

A bolt 35 provided with a rectangular shoulder 36 adapted to slide in the slot 34 is passed through an appropriate hole formed near the lower end of each brace 14, and is held in position by the head 37, washer 38 and nut 39. The lower of the two braces 14 is spaced from the bracket 32 by washer 40. The result of this connection is that each brace 14 may pivot in relation to the strut 19 and the longitudinal 12 to which it is connected, but the two braces connected to a strut 19 can not pivot independently of each other.

It follows that the connection of the braces 14 and thus the connection of the bents to the longitudinals is such that any one bent may move up or down with respect to the remaining bents without any undue strain being imposed thereon and without any joints being broken. Because only one of the bents in any section is fixedly connected to its supporting block, expansion of the longitudinals or the rails results in expansion or contraction, as the case may be, of the entire section, the bents other than the fixed one sliding on their foundation blocks 11, while maintained upright by braces 14.

As appears from Figure 1, two sections are placed end to end but are not in contact. The proximate end bents 10a and 10b are preferably mounted on common foundation blocks 11, but there is left between them an expansion space 41, which is bridged only by the rails 21 and 25, which rails 21 and 25 are at this point provided with an expansion joint illustrated in Figures 3 and 4. Each expansion joint is made up of two sections 35 of rail 21, each having its end diagonally cut at the same angle α to the length of the rail. (See Figure 4.) When the diagonal faces of two rail end sections are placed in contact they form what is in effect a spliced rail as shown in Figure 4.

It will be apparent that because the angle α is relatively small, an appreciable relative longitudinal movement of the two rail end sections may be permitted, without impairing the wheel bearing surface 42 of the rail.

The two rail end sections are held together by means of compression spring 43 contained in position by bolt 44 and its nut 45. As appears from Figure 3, the bolt passes through a hole (not shown) in one rail section end and a slot 46 formed in the other rail section end, approximately half way along the length of the diagonal face, the bolt moving in the slot when one or more of the rail end sections moves in relation to the other.

It is preferred that the gauge side of the rail in relation to the direction of travel indicated by the arrow in Figure 4 should be that indicated as B in Figure 4.

As described above, the trestle work is provided with the lower longitudinal 13 carrying the rails 25 and suspended from the upper cross members 17 by means of the rods 26, and from the upper longitudinals 12 by means of the diagonal ties 29. The lower rails 25 carry the loaded car or truck, the load being suspended from the car by means of cable 47 and the ring 48, whereas the upper rails 21 carry the car on the return journey. As will be apparent, the force of braking of the car with its load, when it has reached the unloading zone is borne by the lower longitudinals 13. Because these longitudinals constitute individual units held against lateral movement by means of the struts 18, and suspended from the caps 17 only by the rods 26, the braking load is not placed solely on one bent but is distributed

over a number. At the same time, the braking load is to some extent absorbed and distributed by the diagonal ties 29.

The ramp arrangement shown in Figures 7 and 8 is provided for transferring the unloaded car from the rails 25 to the top rails 21 at the unloading end of the trestlework, and from the top rails 21 down to the lower rails 25 at the loading end of the trestlework. At each end of the trestlework, each of the two rails 21 is provided with an extension 49, bolted to a bracket 50 by bolts 51. The bracket 50 is in each instance, pivotally mounted on a stub-shaft 52, itself mounted in bearings 53 secured to the cap 17 on the outside of each rail 21 and directly in line with the end of the rail 21. Each bracket 50 is provided at the end opposite to that bolted to the extension 49, with a counterweight 54 positioned by means of the set screw 55. At the unloading end of the trestlework the counterweights 54 are so adjusted that the extensions 49 fall into the position shown, but may be readily kicked up by the wheels 23 of the car 22, when the wheels pass between the rails 25 and the extensions 49. At the loading end of the trestlework, the counterweights 54 are adjusted to hold the extensions 49 in the elevated position illustrated, but to permit the extension to be easily lowered into position by the weight of the car 22 returning to the loading position, so that the car may travel down the ramp formed onto the rails 25. The free end of each extension 49 is bevelled from the underside as at 56 so that a smooth join with the lower rail is made. Stops 57 engage the brackets 50 to prevent the extensions from being lifted too far at the loading end by the counterweight 54 and guides 58 extending downwardly on each side of each rail extension 49 near the bevelled end, ensure that the extension is properly aligned with the lower rail. As appears from Figures 7 and 8, the longitudinals 12 connecting the bents between which the rail extensions 49 are positioned are moved out to clear the extensions 49 and cars carried by them. For clarity, the longitudinals are here marked 12A.

While any mode of power for the cars 22 may be used, it is preferred that they be operated electrically by the known automatic controls, which permit the cars to be started, braked and stopped by an operator located at any given control station. The brakes are preferably solenoid operated and adapted to be automatically applied when the car operating current is off and therefore the solenoid is de-energized, and immediately released when the current is switched on. Current is supplied to the car through the rails and for this purpose the trestlework is divided into three zones each separated by a small rail break, namely, loading, travelling and unloading zones. In the travelling zone the current will normally be on at all times, since it will not be desired to start or stop the car except when it is in the loading or unloading zones. When the operator in the loading zone has loaded the car, he sets the desired lever on the car to the forward travel position, and then energizes the rail in the loading zone. This starts the car in forward motion and it continues to travel until it reaches the unloading zone. When the operator there sees the car coming with its load, he energizes the rail there, so that it may be brought to the proper position and then de-energizes the rail, thus applying the brakes and stopping the motor to bring the car to a stop. After the unloading has been completed the operator energizes the rail again and

the car moves along, the wheels raising the rail extensions 49 in passing. The rail is then de-energized to stop the car, the switch on the car is changed to the reverse travel position, and after the rails are again energized the car travels up the ramp formed by the rail extensions 49 and along the upper rails 21 to the loading zone, where it again comes under the control of the loading zone operator. He, after operating the car down the ramp formed by the extensions 49 at that end, stops the car, places the car switch in the forward travel position and the trip to the unloading zone may be repeated after car has been again loaded.

15. What I claim as my invention is:

1. A flexible trestlework conveyor consisting of at least one section comprising a plurality of transverse bents, longitudinal connecting means carried by said bents, a plurality of diagonal braces connected pivotally at one end to the longitudinal connecting means and at the other end pivotally to means connected to a bent and movable vertically with respect to such bent towards and away from said longitudinal connecting means.

2. A flexible trestlework conveyor consisting of at least one section comprising a plurality of transverse bents, foundation means adapted separately to support each bent, one bent of a section being fixedly connected to its foundation means and the remaining bents of the section being mounted to slide longitudinally of the trestlework in relation to their respective foundation means, longitudinal connecting means carried by said bents, a plurality of diagonal braces connected pivotally at one end to the longitudinal connecting means and at the other end pivotally to means connected to a bent and movable vertically with respect to such bent towards and away from said longitudinal connecting means.

3. A flexible trestlework conveyor consisting of a plurality of trestle sections, each section comprising a plurality of transverse bents, longitudinal members connecting said bents near the top, rails supported on the longitudinal members and adapted to carry load transporting apparatus along the conveyor, strut means connecting each end bent of each trestle section to the adjacent bent, and a pair of diagonal braces pivotally connected to the respective longitudinal members at each side of each trestle section with one brace at each side of each bent except the end bent of each trestle section, the other end of each diagonal brace of each pair being connected pivotally to means connected to the bent between the pair and movable with respect to said bent towards and away from the longitudinal members.

4. A flexible trestlework conveyor consisting of a plurality of trestle sections, each section comprising a plurality of transverse bents, foundation members adapted separately to support each bent, one bent of each section being fixedly connected to at least one foundation member and the remaining bents of each section being mounted to slide longitudinally of the trestlework in relation to their respective foundation members, longitudinal members connecting said bents near the top, rails supported on the longitudinal members and adapted to carry load transporting apparatus along the conveyor, strut means connecting each end bent of each trestle section to the adjacent bent, and a pair of diagonal braces pivotally connected to the respective longitudinal members at each side of each trestle section with one brace at each side of each bent except the end

bent of each trestle section, the other end of each diagonal brace of each pair being connected pivotally to means connected to the bent between the pair and movable with respect to said bent towards and away from the longitudinal members.

5. A flexible trestlework conveyor consisting of a plurality of trestle sections, each section comprising a plurality of transverse bents, each bent of each section except the end bents having connected thereto a bracket having an upwardly extending slot, pivot means adapted to slide in said slot, foundation members adapted separately to support each bent, one bent of each section being fixedly connected to at least one foundation member and the remaining bents of each section being mounted to slide longitudinally of the trestle work in relation to their respective foundation members, longitudinal members connecting said bents near the top, rails supported on the longitudinal members and adapted to carry load transporting apparatus along the conveyor, strut means connecting each end bent of each trestle section to the adjacent bent, and a pair of diagonal braces pivotally connected to the respective longitudinal members at each side of each trestle section with one brace at each side of each bent except the end bent of each trestle section, the other end of each diagonal brace of each pair being connected to the pivot means of the bracket connected to the bent between the pair whereby said end of each diagonal brace may be moved with respect to its bent towards and away from the longitudinal members.

6. A flexible trestlework conveyor consisting of a plurality of trestle sections, each section comprising a plurality of transverse bents, each bent

of each section except the end bents having connected thereto a bracket having an upwardly extending slot, pivot means adapted to slide in the slot of each bracket, a pair of spaced longitudinal members connecting said bents near the top and each carrying a rail for a wheeled car, strut means connecting each end bent of each trestle section to the adjacent bent, and a pair of diagonal braces pivotally connected to the respective longitudinal members at each side of each trestle section with one brace at each side of each bent except the end bent of each trestle section, the other end of each diagonal brace of each pair being pivotally connected to the pivot means of the bracket connected to the bent between the pair whereby said end of each diagonal brace may be moved with respect to its bent towards and away from the longitudinal members.
